CLAIM

The ornamental design for a paraffin wax machine, as shown and described.

DESCRIPTION

FIG. 1 is a perspective view of a paraffin wax machine showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a left-side elevational view thereof; and,

FIG. 7 is a right-side elevational view thereof.

The broken lines in the drawings depict part of the paraffin wax machine that form no part of the claimed design.
